TILTABLE AND VERTICALLY ADJUSTABLE
BEDSIDE TABLE

William H. Lewis, Rockford, Ill.

Application May 18, 1949, Serial No. 93,959

1 Claim. (Cl. 311—27)

1

This invention relates to an adjustable table and more particularly to an adjustable bedside table.

An object of the invention is the provision of a table of the above character having novel means for mounting the table top, that permits the table top to be swung from a position in which it overlies the bed, to be used by an occupant thereof, to a position in which it is adjacent the head of the bed and is disposed in a plane common or substantially parallel with the head so that a patient or occupant of the bed is accessible from either side of the bed.

Another object of the invention is the provision of a table of the above character having novel means for securing the table top to the bed.

Other objects and advantages of the invention will become apparent from the following detailed description taken in connection with the accompanying drawings, in which:

Figure 1 is a perspective view of a table embodying the present invention and a bed with the table top in an inclined position and overlying the bed;

Fig. 2 is a sectional view showing details of construction of the tubular upright, the table top and the means for securing the table top to the upright; and

Fig. 3 is a sectional view taken substantially along the lines 3—3 of Fig. 2.

Referring now to the drawings the invention is shown embodied in an adjustable bedside table attached to a bed so that the table top may be swung between positions in which it is accessible to a person occupying the bed and a position in which it is disposed at one side of the bed in an out-of-the-way position. The bed may be of any conventional construction such as used in the home or in a hospital. For purposes of simplifying the drawings, only the head 12 and a rail 13 of the bed are shown. The rail 13 interconnects the head 12 and a foot (not shown) in a conventional manner. In general the bedside table comprises a table top 14, an arm 16 supporting the table top 14, an upright 17 supporting the arm 16, a horizontal arm 18 extending from the upright and mounting means 19 arranged to be secured to the rail 13 of the bed to provide an axis about which the arm 18, upright 17, and table top 14 are free to swing so that the table top may be moved from a position in which it overlies the bed to a position in which it is folded away at one side of the bed as seen in Figure 1 so that the upright 17 is adjacent the head 12 of the bed and the table top is in a vertical plane common with

2

the head 12. As best seen in Figs. 1 and 2 the table top 14 has a generally rectangular configuration having an upstanding rim 21 formed along its edges. The top 14 may be formed of any suitable material such as wood, synthetic resin or metal. The arm 16 herein is in the form of a cross extending transversely from the top of the upright 17. The table top 14 is secured to the arm 16 as by screws or the like so that the arm 16 provides a rigid support for the table top 14.

Provision is made for adjusting the inclination of the table top 14 so that the position of the top may be varied to suit the individual using the table. For this purpose the arm 16 is mounted on the upright 17 for rotation about a horizontal axis and is provided with a latch for maintaining the table top 14 in any of a number of pre-selected positions about the horizontal axis. The construction for accomplishing this includes a

boss 22 (Fig. 2) formed at one end of the arm 16 and having a smooth bearing surface 23 abutting against an adjacent surface 24 formed on a cap 26 supported by the upright 17. The cap 26 is formed with a bearing opening 27 shaped to receive a smooth shank portion 29 of a headed screw 28. The latter is also formed with a threaded portion 31 receivable in a threaded passageway formed in the boss 22. The length of the shank portion 29 of the screw is substantially the same as the width of the cap 26 so that when the screw 28 is tightened the cap 26 is snugly disposed between the head of the screw 28 and the boss 22. Thus the shank portion 29 defines a pivot or bearing about which the table top 14 is rotatable. A set screw 32 engageable with the threaded portion 31 of the screw 28 secures the latter in position.

The locking means includes a plunger 33 passing through a horizontal passage formed in the cap 26 in spaced relation to the passageway 27. At its inner end the plunger 33 is shaped to be received in one of the apertures 36 formed in the bearing face 23 of the boss 22 and spaced about the opening for the threaded portion 31 of the screw 28. A spring 34 acting between the cap 26 and a collar 37 on the plunger 33 urges the plunger in a direction to have its forward end received in one of the apertures 36.

The upright 17 is formed by two tubular members 38 and 39, the tubular member 38 telescoping into the tubular member 39 so that the height of the table top 14 may be adjusted to preselected elevations. The cap 26 is carried on the tubular portion 38 and has a portion 41 shaped to be received in the hollow passageway of the tubular

member 38. A screw 42 threaded through the side walls of the tubular member 38 and into the body portion 41 of the cap secures the cap to the tubular portion 38. The tubular portion 38 is formed with a row of spaced apertures 43 along one side and the tubular member 39 is formed with an aperture 44 disposed to be in alignment with a selected one of the apertures 43 in the tubular member 38. A pin 46 passing through the aperture 44 and receivable in one of the apertures 43 in the tubular member 38 maintains the tubular members 38 and 39 in a desired adjusted relation to maintain the table top 14 at a preselected elevation. At its lower end the tubular member 39 is provided with a caster holder 47 secured in position by a screw 48. A caster 49 has its stem secured in the caster holder 47 in a conventional manner.

The arm 18 may be a tubular member, as shown in Fig. 3. At one end it is secured to a boss 51 formed on a sleeve 52 as by a screw 53. The sleeve 52 is shaped to snugly receive the tubular member 39 of the upright 17 and is slideable relative to the tubular member 39 so that the height of the arm 18 may be adjusted to correspond to the height of the bed rail 13. A thumb screw 54 threaded through the sleeve 52 and abutting against the tubular member 39 secures the sleeve 52 and the arm 18 in a desired adjusted position along the tubular member 39.

The form of the mounting means 19 may vary considerably depending on the form of the bed rail 13 to which the arm 18 is attached. In general it includes a member secured to the bed rail 13 by suitable means such as clamps, screws or the like and providing a pivotal support for the arm 18. In this instance the mounting means includes a bracket 56 secured to the side of the bed rail as by screws 57. The bracket 56 is mounted on the rail 13 at a position spaced from the head 12 equal to the length of the arm 18. Thus when the arm 18 is in the position shown in solid lines in Figure 1 the table top 14 overlies the bed and when the arm 18 is in the dotted line position shown in Figure 1 the upright 17 is adjacent the head 12 and the table top may be disposed in a vertical plane. The top surface of the bracket is relatively smooth to define a bearing surface for supporting a member 58. The latter is secured to the opposite end of the tubular member 18 as by having a portion 59 of the member 58 received in the opposite end of the tubular member 18 and secured therein as by a screw 61. The member 58 is formed with a vertically arranged bearing opening 62 shaped to receive the smooth shank portion 63 of a vertically arranged screw 65, the latter being threaded into a threaded passageway 66 formed in the bracket 56. This construction in effect defines a vertical pivotal axis about which the arm 18, and in turn the table top 14 are free to move.

Assuming that the bracket 56 has been secured to the rail 13 and the sleeve 52 adjusted relative to the upright 17 so that the upright is securely supported and the caster 49 rests on the floor, the manner in which the table may be used is readily apparent by viewing Figure 1. In the solid line position of the parts it will be noted that the arm 18 is adjacent the rail 13, the upright 17 extends upwardly along the side of the bed and the table top 14 overlies the bed. The elevation of the table top may be adjusted by removing the pin 46 from the tubular members 38 and 39 and moving the tubular member 38 to a position in which the table top 14 is at a desired height.

When the table top is at the desired elevation the pin 46 is inserted in the aperture 44 and in an aperture 43 in the tubular member 38 in registry with the aperture 44. It is to be understood that due to the spacing of the apertures 43, the tubular member 38 may have to be moved up or down slightly to align one of the apertures 43 with the aperture 44.

In Figure 1 the table top 14 is shown in an inclined position. Should it be desired to move the table top 14 to a horizontal position, as shown by the dotted line position superimposed on the solid line position, the occupant of the bed grasps the plunger 33 and pulls it in a direction so that the end of the plunger is withdrawn from one aperture 36 and clears the surface 23. The table top 14 is then free to rotate about the horizontal axis defined by the screw 28. When the table top is in a desired adjusted position the plunger 33 is released. The action of the spring 34 urges the end of the plunger into engagement with the surface 23. The angular position of the top 14 is then adjusted until the end of the plunger is received in one of the apertures 36. As soon as the plunger 33 is received in one of the apertures the table top is locked in position and cannot be rotated further until the plunger is withdrawn from the aperture as described above.

When the occupant of the bed is through with 30 the table, an attendant may fold it away. By pushing on the table top 14 the latter is caused to swing about the axis defined by the screw 65 to any desired position at one side of the bed. Thus, the table top 14 may be moved from the 35 solid line position to the dotted line position shown in Figure 1. Thus the arm 18 moves through an arc of substantially 180 degrees. The table top 14 may also be disposed in a vertical plane in side by side relation with the wall of 40 the room and in a plane common to or parallel with the head of the bed.

The above table construction is simple. It may be readily attached to any conventional bed. The 45 table top 14 is readily adjustable to different elevations and inclinations. Also the table top may be readily moved from a position in which it is 50 readily usable by an occupant of the bed to a position in which it is folded away at one side of the bed in an inconspicuous location. When 55 in the latter position as shown by dotted lines in Figure 1, the table top 14 is out-of-the-way so that the occupant of the bed is readily accessible from either side of the bed. The above construction is advantageous where a plurality of beds are in side by side relation as in a ward. When the table tops are folded away they occupy a very minimum of space. The latter is important in that it gives an attendant more working space than conventional constructions provide.

I claim:

In a bed table for a bed having a longitudinal bed rail, a bracket mounted on said bed rail in spaced relation from the head end of the bed, a vertical standard having floor-engaging means at its lower end and provided at its upper end with means for supporting a table top in angularly adjustable relationship with respect to the vertical standard, said table top supporting means being vertically adjustable with respect to the standard, a horizontal arm provided at one end with a vertically extending hollow sleeve for slidably receiving the vertical standard, a vertically extending pivot member mounted on the bracket, a complementary pivot member mounted at the 70 other end of the horizontal arm and coacting

with said pivot member on the bracket to form a pivotal connection for adjustment of the vertical standard toward and away from the bed, said horizontal arm being of a length corresponding to the distance of said bracket from the head end of the bed, whereby said horizontal arm can be moved about its pivotal axis so that the vertical standard extends adjacent the head end of the bed.
